INVENTOR

ELMER A. SPERRY

BY

Herbert H. Thompson
ATTORNEY.

UNITED STATES PATENT OFFICE.

ELMER A. SPERRY, OF BROOKLYN, NEW YORK, ASSIGNOR TO SPERRY GYROSCOPE COMPANY, OF BROOKLYN, NEW YORK, A CORPORATION OF NEW YORK.

MEANS FOR GOVERNING THE ROLLING OF SHIPS.

Application filed September 30, 1916. Serial No. 123,155.

To all whom it may concern:

Be it known that I, ELMER A. SPERRY, a citizen of the United States of America, residing at 1505 Albermarle Road, Brooklyn, 5 New York, in the county of Kings and State of New York, have invented certain new and useful Improvements in Means for Governing the Rolling of Ships, of which the following is a specification.

10 This invention relates to means for governing the motion of ships at sea and has especial reference to controlling the rolling of war vessels. In my patent on ship's gyroscopes, No. 1,150,311, granted Aug. 17, 1915, 15 and on ship stabilizing and rolling apparatus, No. 1,232,619, granted July 10, 1917, I show an apparatus which may be used either to stabilize or roll a ship or similar unstable vehicles. One of the main objects of this invention is to improve upon apparatus of this character and to adapt it especially to the needs of ships of war.

The primary purpose of a battleship is to shoot straight. It has long been appreciated 25 that the rolling and pitching of the ship very seriously impair the effectiveness of gun fire. In studying the characteristics of rolling, it has been found that when vessels, such as battleships and cruisers, roll less 30 than a certain amount, the roll is attended with certain peculiarities, or idiosyncrasies. The roll is found to be fitful and not dependable, the ship generally rolling twice and sometimes three times in the same direction, 35 before rolling back. Therefore it cannot be relied upon in attempting to anticipate the laying of ordnance in elevation for the most effective gunnery. Beyond this critical point in the amplitude of roll of a ship however, true periodicity permanently sets in and becomes therefore perfectly dependable. When this characteristic roll is 40 present, it is found that ordnance may be accurately laid in elevation, and if some device were provided whereby the amplitude may be held constant, then no change need be made in the elevation of the guns, except for change of range. Thus the new system of so-called director firing, that is, firing all 45 guns simultaneously at a certain predetermined point of the oscillation due to the rolling can be brought to a very much higher degree of perfection than ever possible before.

5 The specific object of the invention, then,

is to devise an apparatus for accomplishing this purpose. To this end, I have improved upon and adapted the gyroscopic apparatus disclosed in the above mentioned patents. Another object of the invention is to insure 60 the firing of the guns at the proper point in the period of the roll of the ship.

Referring to the drawings in which, what I now consider to be the preferred forms of my invention are shown:

65

Figure 1 is an elevation of the master or control gyroscopes.

Figure 2 is a plan view thereof.

Figure 3 is a plan view on a much smaller scale of the main stabilizing gyroscopes, also 70 showing diagrammatically the control gyroscopes and the wiring connections between them and the stabilizing gyroscopes.

Figure 4 is a plan view of a modified form 75 of both the control and stabilizing gyroscopes. In this view, for the sake of symmetry, the scale of the control gyroscopes is larger than that used for the stabilizing gyroscopes.

Figure 5 is a sectional view of one of the 80 valves used in this form of invention.

Figure 6 is a sectional view of a relay valve controlled thereby.

Figure 7 is a section on line 7—7, Fig. 4 85 on an enlarged scale.

Figure 8 is a wiring diagram showing the connections for utilizing my device to control the firing of the guns.

Figure 9 is a detail of the master gyroscopes.

90

According to this invention, a device which is responsive to the rolling of the ship is used as a master governor. This device is somewhat similar in its action to a pendulum and consists preferably of one or more gyroscopes, 1 and 2. These gyroscopes are shown mounted on horizontal spinning axes within vertical rings 3 and 4. The rings in turn are pivoted about vertical pivots 5 and 6, within fixed bearing rings 7 and 8. The rings 3 and 4 are coupled for equal and opposite turning about vertical axes by means such as a link 9, pivoted to brackets 10 and 11, extending from said rings. The gyroscopes are mounted on the ship with their spinning axes athwartship (see fore and aft line 12 Figure 2), so that the rolling of the ship will cause precession of the gyroscopes about their vertical axes 5 and 6. The gyroscopes are preferably centralized by means 100

95

100

105

110

2

of compression springs 13 and 14 which bear against pins 16 and 16', slidably mounted in fixed brackets 15 and 15'. A lug 17 extending from ring 4 is adapted to strike either 5 one or the other of pins 15 and 15' when the gyroscope precesses. Preferably a small space is left between the ends of the pins and said lug for purposes hereinafter described. A fixed contact piece 18 is shown attached to 10 vertical ring 3 and is adapted to strike on precession of the gyro, either one or the other of adjustable contacts 19 or 19'. These contacts control the stabilizing or rolling means for the ship.

15 Also projecting from said ring 3 is shown a member 20, yieldingly held between a pair of pivoted arms 21 and 22. The arms may be geared together as by means of gears 23 and are yieldingly pressed toward each other 20 by means of a spring 24. The piston 25, of a dashpot 26 is pivotally connected to a rod 227 extending from one arm so that after being opened the return of the arms 21 and 22 to their closed position under the influence of spring 24 will be retarded by 25 means of the dashpot. A contact 27 is positioned so as to be engaged by a trolley or brush 28 on rod 29, extending from arm 21. Preferably the contact is adjustable by 30 means such as screws 30 and 30'.

The action of this device is as follows:—

As explained above, the object of the invention is to maintain a predetermined amplitude of roll of the ship. As the ship rocks, 35 the contacts 18 and 20 are applied to control the stabilizing or rolling apparatus. If the ship is rolling less than the predetermined amount, the contacts are so arranged as to increase the rolling. If, on the other hand, 40 the ship rolls more than the predetermined amount, the arms 21 and 22 will be opened sufficiently to complete contacts 27 and 28, which, by means such as hereinafter described, 45 reverses the action of the contacts so that the stabilizing or rolling apparatus will then begin to quench the rolling of the ship.

Said stabilizing or rolling apparatus preferably consists of one or more large gyroscopes 31 and 32, firmly secured to the ship. Apparatus of this kind, performing as it does, a double function, may be termed a means for exerting periodic rolling torques 50 on the ship since no matter whether it is rolling or stabilizing the ship, it exerts said torques, the only difference being that in the former case the torques are in synchronism with the roll while in the latter they are displaced 180° in the cycle. The gyroscopes are 55 shown as mounted on horizontal spinning axes 33 and 34 within casings 35, 35' which are pivotally mounted about vertical axes 36, 36' to the frame work 37 of the ship. The gyroscopes are adapted to be spun in opposite 60 directions and are placed with their spin-

ning axes athwart-ships as indicated by arrow 38. The gyroscopes are coupled for equal and opposite precession by means of gears 39 and 40. The power for controlling these gyroscopes from the master gyro may 70 be furnished by a motor 41, which drives continuously in opposite directions a pair of beveled gears 42 and 43 loosely mounted upon shaft 44. A clutch 45 is adapted to be thrown into engagement with a clutch face 75 46 on either of said gears so as to drive the shaft 44 in either direction. Said clutch is controlled by means of a plurality of electro-magnets 47 and 48, which are in circuit with or controlled from the control switches above 80 referred to. Shaft 44 carries a worm 49 which meshes with a worm wheel 50. On the shaft of said worm wheel is mounted a pinion 51 which connects it with gear 40 so that the motor 41 may exert torques about 85 the precessional axes of the two gyros. When the device is operating to quench the rolling of the ship, the shaft 44 is driven in a direction to cause or permit precession of the gyroscopes in the natural direction 90 caused by the rolling of the ship. When the ship first starts to roll, the precession gear will accelerate the precession, but after the rolling has started, the gyroscopes will tend to precess faster than the worm is turned by 95 the motor so that the said worm acts as a brake on the gyroscopes. When the gyroscopes are acting to roll the ship, however, the shaft 44 is rotated in a direction to apply 100 a torque on the gyroscopes in the opposite direction to the natural precession caused by the rolling of the ship. In other words, the action of the precession gear is exactly reversed or displaced substantially 180° with 105 respect to the rolling cycle.

For effecting this purpose, the contacts 27, 28 on gyroscope 1 (Fig. 3) are placed in circuit with an electro-magnet 150 which actuates the reversing switch 151 in the circuit between contacts 19 and 19' and magnets 47 and 48, so that as long as the ship is exceeding 110 a predetermined amplitude, the apparatus will act as a stabilizer, while when said limit is not exceeded, the circuit through magnet 150 will be broken and switch 151 rotated by spring 152 to cause the apparatus to roll the ship.

Preferably, I also provide in connection with my stabilizing and rolling apparatus an automatic means whereby the guns or 115 other ordnance appliances, such as torpedoes and the like, may be fired at predetermined periods in the roll of the ship. By securing through my apparatus a perfectly definite amplitude and period of roll and by providing an automatic apparatus for firing the guns at a predetermined point therein, absolute precision and timing of the fire may be obtained. This apparatus is preferably 120 incorporated as a part of the gyroscopes 1 130

and 2. As above stated the centralizing pins 16 and 16' are normally spaced a short distance from the projection 17 on ring 4, so that a slight amount of precession may 5 take place in either direction before the pins are struck. Contact members 130 and 130' (see Figs. 8 and 9) are provided on the pins while the projection 17 is also made in the form of a contact so that when the gyro- 10 scope precesses in either direction, a circuit will be completed. The outer end of the pins may be also provided with contacts 131 and 131' adapted to strike other contacts 132 and 132', after a predetermined precession 15 has taken place against the action of the centralizing springs 13 and 14. The first pair of the above described contacts constitutes one method for firing the guns when the ship is at one or the other limits of its 20 roll, that is, when the ship is starting to swing back on the reverse roll, since the moment the direction of roll changes the gyroscopes will start to precess in the other direction and hence move against the other 25 contacts 130 or 130'. Contacts 131 and 132, on the other hand, constitute a means for firing the guns when the ship reaches its maximum velocity of roll, which it will be readily understood is normally when it is 30 passing through its horizontal position. As gyroscopes normally maintain a definite amplitude of roll, the position of contacts 130, 132 and the tension of springs 13 and 14 may be nicely adjusted to fire the guns at 35 the exact maximum velocity since the torque exerted by the gyroscopes on the springs due to their precession is directly proportional to the velocity of roll. Other methods of securing the above results, other than by 40 the arrangement of contacts described, will suggest themselves to those skilled in the art.

Means for selecting the proper contacts and controlling the firing of the guns from 45 the same is shown in Fig. 8. In this figure the switch 133 represents the firing button pushed by the Fire Control Officer. As this button is pressed into engagement with contact 134, it displaces the spring pressed 50 catch 135 so that the catch will snap over the button and hold it in engagement with contact 134 until withdrawn. An electromagnet 136 or similar means in circuit with the said button and the above described contacts is designed to withdraw the catch as 55 soon as current flows through the circuit,—in other words, as soon as the guns are fired. A retarding device such as dashpot 170 may be attached to switch 133 to prevent breaking 60 the circuit before the guns are fired. To this end contact 134 may be spring pressed so as to follow the switch a short distance. All of the contacts 130 to 132 are 65 connected through a double throw switch 137 which is designed to cut in a selected

pair of contacts and at the same time cut out the other pair so that the guns may be fired when the ship is horizontal, or when it is at its maximum inclination, as desired. Another switch 138 may also be provided 70 which is designed to select which contact of the two contacts in each pair shall be used to fire the gun. In other words, these switches give the officer means for firing when the ship is passing thru its horizontal position either on the down roll or on the up roll and also when the guns are at either their maximum or minimum elevation. If the ship were firing salvos from both sides at once it is quite conceivable how this apparatus could be made to fire the guns on each side when they are at their maximum elevation, in other words, so that a salvo would be discharged alternately from opposite sides of the ship twice during each 80 roll of the sh'p. In the diagram, the fine platinum wires in the gun cartridges for firing the guns are shown at 140 and the source of electricity at 141.

My invention is, of course, adapted to be 90 embodied in other forms than that shown and described above. For instance, motive fluids other than electricity may be employed to operatively connect the master and stabilizing gyroscopes. Such an embodiment 95 of the invention is shown in Figs. 4 to 7 in which compressed air is employed. In Fig. 4 the master gyroscopes are again shown at 1 and 2 and the stabilizing gyroscopes at 31 and 32. Projecting from the 100 vertical ring 4 of the gyroscope 2 is a bracket 60 to which is attached a plurality of rods 61, 62, 63 and 64 all of which are adapted to be moved axially by the precession of the gyroscope. Rods 64 and 63 are spring 105 pressed so that they will centralize the gyroscope in a manner similar to pins 16 and 16' in the other form of the invention. After a predetermined movement of rod 63 has taken place it will strike the valve rod 65 thereby effecting the displacement of the piston 66 within valve chamber 67. A similar movement of rod 64 causes a similar action within the valve chamber 67'. Rod 61 is connected to the piston 68 of piston valve 69 so that precession of the gyroscope 2 in either direction will displace the said piston. Said valve is connected to the main supply pipe 70 through passage 71 (see Fig. 7). Leading from said valve are two pipes 72, 73 which are connected to the reversing 110 valve 74. Both of the valves 67 and 67' above described are also connected to said reversing valve through the pipes 75 and 76 (see Figs. 4 and 6). Leading from said 115 reversing valve are two pipes 77, 78 which are connected to a cylinder 79 mounted adjacent to the stabilizing gyroscope; the two pipes 77, 78 leading to opposite ends of the cylinder, so that admission of air through 120 125 130

either pipe will move the piston to the opposite end.

The rod 62 is connected to another piston valve 82. Preferably a limited amount of lost motion is allowed between the rod 62 and the bracket 60 in both directions. For this purpose the rod is provided adjacent its outer end with a slot 83 which engages over a pin 84 on bracket 60. The rod is normally centralized with respect to the pin by a pair of springs 85, and 86 which bear at the outer ends against fixed stops 87, 88, but at the inner ends against a member 89 pivotally secured to the end 90 of rod 62 (see Fig. 7). The cylinder 82 is connected to the main supply through pipe 91 and ports 183 and 184 and is connected to a brake cylinder 93 mounted near the stabilizing gyroscope by means of pipe 94. Brake cylinder 93 is connected to an arm 194 pivoted at 95 to which is secured a brake band 96 extending entirely around the casing of gyroscope 31 within a guideway in or on brake drum 97. The brake is normally applied by means of the strong tension spring 98, but the cylinder 93 is so designed as to hold the brake off when supplied with motive fluid. From the construction of valve 82, it will be apparent that the ports are open between the supply and the brake cylinder when the piston 182 is centralized. But when rod 62 is displaced the inlet ports 180 and 183 (or 181 and 184) will be closed, shutting off the main supply and at the same time opening exhaust ports 185 or 186, as the piston moves out from under them. This will at once reduce the pressure in the cylinder 93 and permit spring 98 to apply the brake. In the other form of the invention, the function performed by brake cylinder 93 is accomplished by means of a solenoid 93' in circuit with contacts 155 and 156 on the control gyroscopes. When trolley 155 rolls beyond the end of contact 156, the brake is applied.

The piston of cylinder 79 is connected by means of rod 99 to an arm 100 secured to a segmental gear 101. Also secured to said arm 100 is link 202 pivoted adjacent one end to a spindle block 203. A second link 104 is also secured to said block and is pivoted near its outer end to a bell crank lever 105. A similar bell crank lever 106 is joined thereto by adjustable link 107. Block 203 is normally centralized by means of compression springs 108, 109, which bear adjacent their inner ends against said block and adjacent their outer ends against stops 110 and 111. When the piston in the cylinder 79 is actuated it will not only rotate the gear 101, but will also rock bell crank levers 105, 106 in one direction or the other. A lug or stop 112 on the casing of gyroscope 31 is adapted to strike one or the other of cam surfaces 113 or 113' on levers 105 and 106 when either of them is rocked downwardly so that the

levers will be automatically returned to their normal positions when the gyroscope approaches the predetermined limit of precession.

The gear segment 101 meshes with a pinion 102 which is so connected to a system of change speed gearing enclosed within the casing 103 as to shift said gearing to transmit motion from the constantly driven motor 41 to shaft 44' from the maximum speed in one direction through zero to the maximum speed in the opposite direction. I prefer to employ in this connection the transmission gearing known as the Waterbury change speed gear, which is now employed for controlling the movements of gun turrets on war ships. Shaft 44' is connected to the gyroscopes by means of worm 49, worm wheel 50, pinion 51 mounted on the shaft of the worm wheel and the large gear 40 on the gyroscope 31.

The action of the compressed air or hydraulic system above described is as follows:—

Let us suppose first that the ship is rolling less than the predetermined amount and that the gyroscopic system is acting to increase the roll of the ship. In this position the valves 67, 67' will remain closed while valve 69 would be moved first in one direction and then in the other by the precession of the gyroscopes. The movement of piston 68 would cause air to flow from port 71 alternately into ports 116 and 120 as the piston reverses. This would cause air to flow through pipe 72 into port 112 of valve 74 and from thence out port 113 through pipe 78 to one end of cylinder 79.

Similarly when piston valve 68 moves in the other direction, air will flow through port 120 and pipe 73 into port 121 of cylinder 74 and from thence through the recess in the piston valve and port 122 into pipe 77 which leads to the opposite end of cylinder 79. It will thus be seen that the precession of the gyroscopes 1 and 2 will cause torques to be applied about the precession axes of gyroscopes 31 and 32 in predetermined directions and in synchronism with the natural period of the ship. The levers 105, 106 and stop 112 above described are in the nature of a limit device which automatically stops the precession gear when the main gyroscopes approach the limit of their movement. This limit mechanism is, of course, not always brought into operation when the precession engine is controlled entirely through valve 69, but when a rough sea is encountered the stop mechanism operates and stops the worm 49 irrespective of the position of valve 69.

Returning now to the action of valves 67 and 67', let us suppose that the amplitude of the roll of the ship is approaching the predetermined value. As this value is

reached, port 123 in one or the other of valves 67 and 67' will be uncovered by the impact of rod 63 or 64 with valve rod 65 or 65' (for instance) and air will flow through pipe 75 into one end of the small cylinder 124 forming a part of valve 74. The main piston 125 of valve 74 has secured thereto the piston 126 of cylinder 124 and preferably also a stop rod 127. The piston 125 and its attached piston 126 are normally held in the position shown in the drawing by a compression spring 128, but when air is admitted through pipe 75 or 76 the plunger is forced to the other end of its stroke and the relation of the ports changed so that the air flowing in through pipe 72 will now flow through the recess in the plunger and through port 122 into pipe 77, while air flowing in pipe 73 will flow through port 129 into pipe 78. It will readily be seen that this operation will reverse the connections between the precession valve 69 and the cylinder 79. Cylinder 124 is provided with a graduated release valve 200 so as to permit a gradual, but steady escape of air therefrom whereby the piston 126 will be slowly returned by spring 128, unless the cylinder is supplied at frequent intervals from valves 67, 67'. Additional reservoirs 201 may be provided between the valves and the cylinder to avoid sudden movements of piston 126.

It will be understood, that, as actually constructed, the various parts are made so that they can be readily adjusted or thrown out entirely so that the apparatus may be used at times solely as a stabilizer, at other times solely to roll the ship through any desired angle. Also that, when used to maintain a definite amplitude of roll, that the amplitude may be varied to suit the varying conditions encountered. In the electrical form of the invention, this adjustment is accomplished by shifting the position of contact 27, while in the other form it is secured by adjusting the position of valves 67 and 67' with respect to brackets 171 by resetting the lock nuts 172 on bolts 173 by means of which the valves are bolted to the brackets. (Figures 4 and 5.)

Among the many advantages secured by my invention are the increased accuracy of gun fire, as explained, and a marked reduction in the capacity of stabilizing apparatus required. Thus, to stabilize a battleship in a sea which would normally roll it 10° , to within 1° would require a much more powerful stabilizing unit than that required to maintain a uniform roll of 5° .

In accordance with the provisions of the patent statutes, I have herein described the principle of operation of my invention, together with the apparatus, which I now consider to represent the best embodiment thereof, but I desire to have it understood that

the apparatus shown is only illustrative and that the invention can be carried out by other means. Also, while it is designed to use the various features and elements in the combination and relations described, some of these may be altered and others omitted without interfering with the more general results outlined, and the invention extends to such use. 70

Thus in the use or construction of apparatus according to my invention, only the lower half, or only the upper half so to speak, of the apparatus may be employed. That is, the apparatus might be built, or in any event in a fairly calm sea would operate, only to roll the ship, which means would be thrown out or rendered inoperative beyond a predetermined amplitude. Similarly the stabilizing effect only need be, or in a rough sea, would be employed, 85 which effect would be brought into action when the roll exceeds a predetermined amplitude.

Having described my invention, what I desire and claim by Letters Patent is:— 90

1. The combination with a ship, of means mounted thereon for maintaining a roll of predetermined amplitude and gyroscopic governing means for causing said other means to act in the natural period of the ship. 95

2. The combination with a ship, of means for exerting periodic rolling torques thereon, and means responsive to the amplitude of the ship's roll for governing the action 100 of said other means to maintain a rolling motion of predetermined magnitude.

3. The combination with a ship, of means for exerting rolling torques thereon, and means responsive to the amplitude of the ship's roll for changing the phase relation 105 of the torques applied with respect to the roll of the ship by substantially 180° .

4. The combination with a ship, of a gyroscope mounted therein for exerting periodic rolling torques thereon, and means responsive to the amplitude of the ship's roll for changing the direction of the torques applied with respect to the roll of the ship. 110

5. The combination with a ship, of a gyroscope mounted therein for exerting torques thereon, means for applying periodic torques on said gyroscope about its precessional axis, and means responsive to the amplitude of the ship's roll for governing the synchronism of the torque on the gyroscope and the roll of the ship. 115

6. The combination with a ship, of a gyroscope mounted therein for exerting torques thereon, means for applying periodic torques on said gyroscope about its precessional axis, and means responsive to the amplitude of the ship's roll for governing the synchronism of the torque on the gyroscope and the torque exerted by the gyroscope. 125

7. The combination with a ship, of a gyroscope mounted therein for exerting torques thereon, means for applying periodic torques on said gyroscope about its precessional axis, means responsive to a predetermined precession of the first gyroscope for shifting said gearing irrespective of said other responsive means.
8. The combination with a ship, of a gyroscope mounted therein for exerting periodic rolling torques thereon, and means responsive to the amplitude of the ship's roll for changing the direction of the torques applied with respect to the roll of the ship and for applying a brake on the gyroscope.
9. The combination with a ship, of means for exerting periodic rolling torques thereon, a gyroscope mounted thereon for precession on rolling thereof, and means responsive to a predetermined precession of said gyroscope for changing the direction of the torques applied with respect to the roll of the ship.
10. The combination with a ship, of a gyroscope mounted thereon for exerting periodic rolling torques thereon, a second gyroscope for controlling said first gyroscope, and means responsive to a predetermined precession of said second gyroscope for changing the direction of the torques applied by the first gyroscope with respect to the roll of the ship.
11. The combination with a ship, of a gyroscope mounted therein for exerting torques thereon, means for applying periodic torques on said gyroscope about its precessional axis, a second gyroscope, means responsive to precession of said gyroscope for controlling said means, and means responsive to a further precession of said gyroscope for reversing the operative connections between said controlling and said torque applying means.
12. The combination with a ship, of a gyroscope mounted therein for exerting torques thereon, means for applying periodic torques on said gyroscope about its precessional axis, comprising a continuously driven motor, reversing gearing between said motor and the gyroscope, fluid operated means for shifting said gearing, a second gyroscope, and means responsive to a predetermined precession of the second gyroscope for operating said fluid means.
13. The combination with a ship, of a gyroscope mounted therein for exerting torques thereon, means for applying periodic torques on said gyroscope about its precessional axis, comprising a continuously driven motor, reversing gearing between said motor and the gyroscope, fluid operated means for shifting said gearing, a second gyroscope, means responsive to a predetermined precession of the second gyroscope for operating said fluid means, and other
- means responsive to a predetermined precession of the first gyroscope for shifting said gearing irrespective of said other responsive means.
14. The combination with a ship of a gyroscope mounted thereon for precession relative thereto, means for exerting periodic rolling torques on the ship, a valve actuated by precession of the gyroscope, fluid pressure means governing the application of said torques, a reversing valve in the connections between said other valve and said fluid pressure means, and a limit valve actuated only upon a predetermined precession of said gyroscope for controlling said reversing valve.
15. The combination with a ship, of a gyroscope mounted thereon for precession relative thereto, means for exerting periodic rolling torques on the ship, a member displaceable by the precession of said gyroscope yielding means for returning said member, means whereby said return is retarded, and means responsive to the position of said member for controlling said rolling means, a valve actuated by precession of the gyroscope, fluid pressure means governing the application of said torques, a reversing valve in the connections between said other valve and said fluid pressure means, and a limit valve actuated only upon a predetermined precession of said gyroscope for controlling said reversing valve.
16. The combination with a ship, of a gyroscope mounted thereon for precession relative thereto, centralizing means for said gyroscope, means for exerting periodic rolling torques on the ship, a valve actuated by precession of the gyroscope, fluid pressure means governing the application of said torques, a reversing valve in the connections between said other valve and said fluid pressure means, a limit valve actuated upon a predetermined precession of said gyroscope for shifting said reversing valve, and a yielding and retarding means for slowly returning said valve.
17. The combination with a ship, of means for exerting rolling torques thereon alternately in opposite directions, including a control device for said means for causing reversal of said torques when the roll of the ship reverses, and means responsive to an increase in amplitude of the ship's roll beyond a predetermined amount, for causing said control means to cut out said torque applying means until said amplitude returns to normal.
18. The combination with a ship, of means for exerting rolling torques thereon in a direction to stabilize the ship, and means responsive to a decrease in the amplitude of the ship's roll for throwing said means out of action.
19. The combination with a ship, of a

gyroscope mounted therein for exerting periodic rolling torques thereon, and means responsive to an increase in amplitude of the ship's roll beyond predetermined amount 5 for rendering said gyroscope inoperative to roll the ship until said amplitude returns to normal.

20. The combination with a ship, of a gyroscope mounted therein for exerting rolling torques thereon to roll the ship, and means responsive to the rolling of the ship beyond a predetermined amount, for rendering said gyroscope operative to stabilize the ship.

15 21. The combination with a ship, of means for exerting rolling torques thereon, a gyroscope mounted thereon for precession on rolling thereof, and means responsive to a predetermined precession of said gyroscope 20 for governing the action of said means.

22. The combination with a ship, of a gyroscope mounted thereon for exerting rolling torques thereon, a second gyroscope for controlling said first gyroscope, and means 25 responsive to a predetermined precession of said second gyroscope for rendering said gyroscope inoperative to roll the ship.

23. The combination with a ship, of a means thereon for applying rolling torques

on the ship, a control gyroscope mounted 30 for precession on rolling of the ship, means for governing the action of said rolling means from said gyroscope, and means responsive to the extent of precession of said gyroscope for altering the action of said 35 governing means.

24. The combination with a ship, of a means thereon for applying rolling torques on the ship, a control gyroscope mounted for precession on rolling of the ship, means for 40 governing the action of said rolling means from said gyroscope, and means responsive to the extent of precession of said gyroscope for reversing the action of said governing means to cause the torques exerted 45 by said first means to oppose rolling.

25. The combination with a ship, of a stabilizing means thereon, a governor for said means responsive to the amplitude of ship's roll, and means connecting said governor and stabilizing means adapted to prevent operation of said stabilizing means unless the roll of the ship exceeds a predetermined amplitude.

In testimony whereof I have affixed my 55 signature.

ELMER A. SPERRY.
